UNITED STATES PATENT OFFICE

JACOB TELLER, OF CHICAGO, AND ARTHUR P. SCHULZ, OF BERWYN, ILLINOIS, AS-
SIGNORS TO TELLER CORPORATION, OF CHATTANOOGA, TENNESSEE, A CORPORATION
OF TENNESSEE

DESIGN FOR A GAS OR ELECTRIC RANGE

Application filed April 7, 1931. Serial No. 39,396. Term of patent 7 years.

To all whom it may concern:

Be it known that we, JACOB TELLER and ARTHUR P. SCHULZ, citizens of the United States, and legal residents respectively of Chicago and Berwyn, in the county of Cook and State of Illinois, have invented a new, original, and ornamental Design for a Gas or Electric Range, of which the following is a specification, reference being had to the accompanying drawings, forming a part thereof.

Figure 1 is a front perspective view of the range with the top raised, and

Figure 2 is a similar view showing our new design with the top closed.

We claim:

The ornamental design for a gas or electric range, as shown and described.

JACOB TELLER.

ARTHUR P. SCHULZ.
